UNITED STATES PATENT OFFICE.

ALFRED SMALLWOOD, OF LONDON, ENGLAND, ASSIGNOR TO THE INCANDESCENT HEAT COMPANY LIMITED, OF LONDON, ENGLAND.

MUFFLE OR FURNACE FOR ANNEALING.

No. 838,641.

Specification of Letters Patent.

Patented Oct. 16, 1906.

Original application filed January 19, 1905, Serial No. 241,904. Divided and this application filed October 2, 1906. Serial No. 280,940.

To all whom it may concern:

Be it known that I, ALFRED SMALLWOOD, of 52 Gracechurch street, London, in the county of Middlesex, England, have invented certain new and useful Improvements in Muffles or Furnaces for Annealing; and I hereby declare that the following is a full, clear, and exact description of the same and that this application is a division or continuation of my application for Letters Patent of the United States for the same invention filed January 19, 1905, Serial No. 241,904.

In the case of furnaces for annealing tubes, sheets, rods, and other metal articles, and which furnaces are applicable for use in connection with glass, pottery, and various other classes of articles, such furnaces consist of an annealing-chamber with a combustion-chamber which is arranged intermediately between the fire-grate and the annealing-chamber, with a fire-brick, fire-clay, or other suitable partition between the two which in work becomes incandescent throughout and which assists in igniting the uncombusted gases as they pass from the fire-grate through the combustion-chamber to the heating or annealing chamber, the object being to distribute those parts of the furnace which require to be in a state of incandescence, so as to obtain a more rapid ignition of the gases in proportion to the size of the combustion-chamber, and at the same time render most of the surrounding lining of the annealing-chamber incandescent throughout, by which a more effective distribution of the heat is obtained. By this arrangement the heated gases less the amount absorbed by the articles under process of annealing can be conveyed to a second and even a third annealing-chamber, thereby saving the fuel which would otherwise be required for heating the one or two successive chambers, while at the same time either or any of such annealing-chambers can be more readily converted, so as to be applicable for either "close" or "open" annealing, as may be required.

The combustion-chamber is placed under the annealing-chamber, with the fire-grate arranged at the rear or side of the combustion-chamber so as to be farthest removed from the heat-exit, the roof or division between the two chambers being constructed with fire-bricks, fire-clay, or other material of a kind which is suitable for becoming incandescent

under heat, the lower side of the roof of the 55 combustion-chamber being so designed and constructed as to increase its power of acting as an accumulator and retarder of heat which has been generated in the combustion-chamber and otherwise to form a means whereby 60 practically complete combustion can be assisted.

In order to form the heat-accumulator and obtain the desired result, the roof is designed and constructed as to increase the area of 65 the lower side thereof by corrugated, draft-board, or other surface extensions, projections, or excrescences which extend or project into the combustion-chamber sufficiently to assist in breaking up, mixing, and circulating 70 the uncombusted material and gases and render them more amenable in their combustion with the oxygen.

In furnaces for annealing certain articles, including some classes of tubes for the prevention of oxidation, it is necessary that they should not be exposed or in any way subjected to the external atmosphere when under the process of annealing, and this invention is shown applied to furnaces which are capable of being made convertible, so as to admit of either close or open annealing being effected.

In the drawings, Figure 1 is a section illustrating the application of this invention to 85 furnaces which are convertible to either close or open annealing. Fig. 2 is a transverse section through Fig. 1 on the line 1^A 2^A. Fig. 3 is a sectional plan through Fig. 2 on the line B B, that portion of the plan illustrating the left-hand half of the section being inverted to show the roof of the combustion-chamber.

Like letters and numerals of reference refer to like parts throughout the specification and drawings.

In applying this invention to annealing chambers, as illustrated more particularly by Figs. 1, 2, and 3, a cavity b' is provided in the side walls of the annealing-chamber, and such cavity is extended down to the combustion-chamber at 1, at the several points where not required for the support of the floor of the annealing-chamber and in some cases above the arch of the annealing-chamber, the lower part of the cavity in the roof of the combustion-chamber B being enlarged 100 at the mouth 2, so as to readily admit of the

heated gases rising up into and flowing through to the cavities for the purpose of rendering the lining of the annealing-chamber incandescent throughout, a number of 5 fire-bricks or blocks of suitable material in some cases being built into the lining at 1^a, so as to project at intervals across the cavity to assist in conducting the heat to the lining 3.

The combustion-chamber B is located in 10 the same horizontal plane as the furnace B', and above the combustion-chamber B is the annealing-chamber H, separated from the combustion-chamber by a horizontal partition B'', having surface extensions C projecting downwardly into the combustion-chamber. The horizontal partition B'' and the surface extensions C are of a material capable of becoming incandescent, so that the heat from the combustion-chamber can be absorbed by the horizontal partition B'' and extensions C and radiated by them into the annealing-chamber.

In order to assist in forming an accumulation of heat, the surface extensions or projections C are arranged to extend or project into the combustion-chamber B sufficiently to also assist in breaking up, mixing, and circulating the uncombusted materials.

For facilitating the conversion of the furnace from one for open annealing to one for close annealing, in which the chamber is hermetically sealed during the annealing of the articles, the heat-exit from the combustion-chamber B is effected by one or more vertical flues 4, arranged to convey the heat from the combustion-chamber B into and directly through the annealing-chamber H for open annealing and one or more vertical flues 5, connected with the flue 6 above the annealing-chamber H, horizontal dampers 7^a 7^b being fitted to each pair of flues 4 and 5 in such a manner that by opening the one damper and closing the other either flue can be closed and the other one at the same time opened, thus rendering it possible to either pass the heat through the chamber H by the flues 4, as when required for open annealing, or over the top of the chamber by flues 5, as required for closed annealing. The opening 7 is provided in the top H' of the annealing-chamber for allowing of the passage of the heated gases in the case of open annealing, while the opening 8 is provided for the escape of the gases in the case of close annealing, the opening 7 being then closed by its damper 9.

The top flue 11 is provided for conveying the gases to the stack-flue 12 when the open-

ing 10 is closed by its damper, as in the case of close annealing being effected.

Having thus fully described my invention, 60 what I claim as new, and desire to secure by Letters Patent, is—

1. A muffle or annealing-furnace comprising a fire-grate, a combustion-chamber in the same horizontal plane as the fire-grate, an 65 annealing-chamber arranged above the combustion-chamber so that the latter will be intermediately located between the fire-grate and the annealing-chamber, a horizontal partition capable of becoming incandescent separating the combustion-chamber from the annealing-chamber and forming the floor of the annealing-chamber, surface extensions forming part of said partition and of the same material thereas and projecting into 75 the combustion-chamber in the path of the gases passing therethrough, vertical partitions connected to the roof of the annealing-chamber and to said horizontal partition and of the same material as the latter, and extensions of the combustion-chamber at the sides of said vertical partition.

2. A muffle or annealing-furnace comprising a fire-grate, a combustion-chamber in the same horizontal plane as the fire-grate, an 85 annealing-chamber arranged above the combustion-chamber so that the latter will be intermediately located between the fire-grate and the annealing-chamber, a horizontal partition capable of becoming incandescent 90 separating the combustion-chamber from the annealing-chamber and forming the floor of the annealing-chamber, surface extensions forming part of said partition and of the same material thereas and projecting into 95 the combustion-chamber in the path of the gases passing therethrough, vertical partitions connected to the roof of the annealing-chamber and to said horizontal partition and of the same material as the latter, and extensions of the combustion-chamber at the sides of said vertical partition, flues leading 100 from the combustion-chamber into the annealing-chamber, other flues leading out of the annealing-chambers, and dampers to 105 control the passage of the gases from the combustion-chamber into the annealing-chamber and out of the annealing-chamber.

In witness whereof I have hereunto set my hand in the presence of two witnesses.

ALFRED SMALLWOOD.
